UNITED STATES PATENT OFFICE.

THOMAS FELPS, OF CLINTON, LOUISIANA.

COTTON-SCRAPER ATTACHMENT FOR PLOWS.

SPECIFICATION forming part of Letters Patent No. 270,654, dated January 16, 1883.

Application filed October 31, 1882. (Model.)

To all whom it may concern:

Be it known that I, THOMAS FELPS, a citizen of the United States, residing at Clinton, in the parish of East Feliciana and State of Louisiana, have invented certain new and useful Improvements in Cotton-Scraper Attachments for Plows, of which the following is a specification, reference being had therein to the accompanying drawings, in which—

10 Figure 1 is a perspective of a plow provided with my improved cotton-scraper; Fig. 2, a bottom view, the scraper being shown in dotted lines; Fig. 3, a side elevation of the plow proper, and Fig. 4 a perspective of the scraper

15 detached.

Like letters refer to like parts in all the figures.

A represents the handles, B the beam, and C the plow proper as usually constructed, the 20 latter element in this instance consisting of a single casting comprising a standard, c, and base c', united to form a landside and a mold-board, c², terminating at a shoulder, c³, forming, with the remaining conformation of the 25 casting, a seat, c⁴, for an ordinary plow-point, which is secured in proper position by a bolt or screw, c⁵.

D represents my cotton-scraper; and it consists of suitable wrought or cast steel or other 30 suitable metal, adapted to be secured in the position of and by the same means that retains the ordinary plow-point to the plow proper. The scraper has a rounded and curved point, d, an upwardly-curved and rearwardly and up- 35 wardly inclined landside-edge, d', which projects laterally beyond the beam, a straight base, d², and in its upper side or edge a recess, d³, the bottom line, d⁴, of which is adapted to fit the shoulder c³ of the casting C, while the 40 sides d⁵ d⁶ of the recess fit the landside and

mold or turning board edges of the plow proper, respectively, as clearly shown in Fig. 1. A hole, d⁷, formed in the scraper, is formed for passage of bolt or screw c⁶.

By the construction thus set forth it will be 15 seen that an ordinary turning-plow may be quickly transformed into a cotton-scraper plow by simply removing the ordinary point and securing in its place the scraper. The side walls of the recess d³ prevent any pivotal turning of the scraper on the screw, and therefore 50 it is apparent that in the absence of the shoulder c³ a single bolt will be sufficient to hold the scraper in operative position.

The operation of the scraper and manner of 55 using the same is that commonly practiced, and is not necessary to be described.

Having described my invention, what I claim as new, and desire to secure by Letters Patent, is—

1. A scraper adapted to be attached to an ordinary plow, and consisting of the plate D, having the recess d³, the walls d⁴ d⁵ d⁶ of which are formed to fit the shoulder c³ and land and mold-board edges of a plow, and having the 65 rounded and curved point d and the upwardly-curved edge d', substantially as shown and described.

2. The combination of the plow C, having the shoulder c³ and screw or bolt c⁶, and the 70 scraper D, having the hole d⁷, recess d³, rounded curved point d, and upwardly-curved side edge, d', substantially as shown and described.

In testimony whereof I affix my signature in presence of two witnesses.

THOMAS FELPS.
